US0D1030412S

(12) United States Design Patent (10) Patent No.: US D1,030,412 S
(45) Date of Patent: * Jun. 11, 2024

(54) TACO HOLDER

(71) Applicant: Brenton Burch Gilmore, South Dennis, MA (US)
(72) Inventor: Brenton Burch Gilmore, South Dennis, MA (US)

() Term: 15 Years

(21) Appl. No.: 29/919,539

(22) Filed: Dec. 5, 2023

(51) LOC (14) Cl. 07-06

(52) U.S. Cl.

USPC D7/504

(58) Field of Classification Search

USPC D6/682.2; D7/403, 500, 504, 553.1, D7/553.2, 566, 570, 586, 587, 590, D7/600.1-6, 601, 602, 701, 558, 559, D7/600.1-4; D24/227; D30/130, 133
